UNITED STATES PATENT OFFICE.

PERCIVAL HARRIS, OF NEW YORK, N. Y.

WIG FOR DOLLS.

Application filed November 23, 1926. Serial No. 150,351.

This invention relates to wigs for dolls and has for an object to provide an improved construction wherein the wig is caused to present a desirable appearance and at the same time present mechanical features in such a manner as to permit the wig to be quickly and easily applied to a head.

A further object of the invention is to provide a wig for dolls wherein the body or principal part may be formed from a straight flexible structure capable of being distorted until it properly fits the head.

A still further object of the invention is to provide a wig wherein means simulating hair is presented and separate means held in place by adhesive simulating coiled plats are presented.

In the accompanying drawings—

Figure 1 is a plan view showing part of a wig disclosing certain features of the invention, the wig being shown before it is positioned to fit a head.

Figure 2 is a three-fourths rear perspective view of a doll's head with the body of the wig shown partly applied thereto.

Figure 3 is an enlarged fragmentary view showing part of one end of the wig shown in Figure 1 and illustrating how the ends are knit.

Fig. 4 is a rear view of a complete wig illustrated on a head.

Figure 5 is a fragmentary sectional view through Figure 4 on line 5—5, the same illustrating how the coils are held in place by adhesive.

Figure 6 is an enlarged fragmentary view illustrating the twisted artificial hair used in making the respective coils shown in Figures 4 and 5.

Figure 7 is a view similar to Figure 4 but showing a slightly modified structure wherein the coils are made from artificial hair platted.

In forming a wig according to the present invention artificial hair made of any desired material is used, the particular showing illustrating artificial hair with a faked or imitated plat in the preferred form of the invention and a genuine plat in the modified form of the invention.

In Figure 1, the body of the wig is shown spread out consisting of the artificial hairs or yarn 1 connected together by a central member 2 which is in fact, a line of knitting.

This line of knitting forms the part when the wig is in place on the head. On each

end of the body 1 are knit sections 3 and 4 which are knit in any desired manner and form comparatively stiff sections which may receive adhesive for holding the wig in place on a head or may receive thread, pins, tacks or other securing means which readily connect these members to the head.

When the body is to be placed on the head, the body is grasped at each end and placed against the head in such a manner that the knitting or part 2 will be at the desired point on the head and then the side members or portions of the body will be moved down over the sides of the head and pulled into the desired shape and position as shown in Figures 2 and 4. The head 5 shown in the accompanying drawings, is a head well known on the market and is provided with a cloth outer surface which extends over the face as well as the back and neck. It is, of course, evident that the wig could be applied to other forms of head without departing from the spirit of the invention.

When the parts are pulled down to the desired position, staples, pins, stitching or other securing means are passed through the respective ends 3 and 4 and into or through the head 5. This holds the body of the wig in proper position. Heretofore, the body

was held in position by stitching principally and was made of such a length that one or more plats could be formed from the depending part of the wig. In the present invention, this is not true, but the body as shown in Figure 1, is only long enough to extend down to about the neck. After the body has been placed in position, any desired number of coils 6, 7 and 8 are placed at the lower edge of the body so as to give a finished appearance to the wig.

These coils are made independently of the wig and preferably from two strands, namely, strands 9 and 10, said strands being twisted independently for forming bunches or loops 11 and then twisted again to form what appears to be a plat 12. A section of this specially formed structure as shown in Figure 6, is wound into a coil as shown in Figures 4 and 5 and then is provided with adhesive, after which, the adhesive side is

pressed against the wig and doll head so that the coils will be positioned substantially as shown in Figure 4. It is difficult, if not impossible, to apply adhesive to the coil or to the head by a brush or other well known means and, consequently, an improved

method has been provided which consists in applying a coating of adhesive to a flat surface, as for instance, a board, then placing one or more coils on the board on top of the adhesive, pressing once or more the various coils so that they will be given a slight back and forth movement while in contact with the adhesive and finally removing the coils from the board carrying the adhesive and placing the same in the desired position on the head. When the coils are placed on the head and pressed against the same, the parts which are pressed against the head and lower part of the body of the wig will have adhesive thereon by reason of the particular method used in applying the adhesive. This will cause the coils to firmly adhere and will require a minimum amount of work in applying.

In Figure 7, a slightly modified construction is shown wherein the various coils 6', 7' and 8' are made from yarn consisting of artificial hair and are platted in the usual way. Preferably, a long plat is made by hand or partly by hand and partly by machinery, then a desired length is cut off, wound into the coil and then applied as above described. After the coils have been applied, the wig is completed and in position. If desired, the body 1 could be placed on a form and the coils applied thereto as above described and then removed and sewed, though ordinarily, it has been found better to apply the wig to the individual head as above described.

What I claim is:

1. A doll's wig comprising a body formed of a plurality of strands of yarns arranged

substantially parallel and means at each end of the various strands for connecting the strands together while leaving the strands substantially parallel, means extending through said ends for connecting the body to a doll's head, a plurality of members simulating coils of platted hair, and adhesive connecting said coils with the body.

2. A doll's wig comprising a body formed of a plurality of yarns arranged substantially parallel, a central line of knitting interlocking with said strands of yarn presenting a part effect, end sections of knitting interlocking with said strands of yarn for connecting the ends of the yarn together, and means co-acting with said end sections for holding the body in place on a head.

3. In a doll's wig a body formed of yarn simulating hair and constructed to present a rectangular member, a centrally positioned line of knitting extending transversely of the body, and end sections of knitting extending for the full width of the body.

4. A wig comprising a body, means for holding the same on a head and means co-acting with said body presenting what appears to be coils of hair, said means consisting of a coiled member formed of a pair of twisted strands, each strand being independently twisted with constricted portions and loose portions, the loose portions presenting means simulating sections of a platted strand.

5. A doll's wig comprising a body, a plurality of members simulating platted knots of hair, and adhesive covering one face of each knot connecting said knots to the body.

PERCIVAL HARRIS.

method has been provided which consists in applying a coating of adhesive to a flat surface, as for instance, a board, then placing one or more coils on the board on top of the adhesive, pressing once or more the various coils so that they will be given a slight back and forth movement while in contact with the adhesive and finally removing the coils from the board carrying the adhesive and placing the same in the desired position on the head. When the coils are placed on the head and pressed against the same, the parts which are pressed against the head and lower part of the body of the wig will have adhesive thereon by reason of the particular method used in applying the adhesive. This will cause the coils to firmly adhere and will require a minimum amount of work in applying.

In Figure 7, a slightly modified construction is shown wherein the various coils 6', 7' and 8' are made from yarn consisting of artificial hair and are platted in the usual way. Preferably, a long plat is made by hand or partly by hand and partly by machinery, then a desired length is cut off, wound into the coil and then applied as above described. After the coils have been applied, the wig is completed and in position. If desired, the body 1 could be placed on a form and the coils applied thereto as above described and then removed and sewed, though ordinarily, it has been found better to apply the wig to the individual head as above described.

What I claim is:

1. A doll's wig comprising a body formed of a plurality of strands of yarns arranged

substantially parallel and means at each end of the various strands for connecting the strands together while leaving the strands substantially parallel, means extending through said ends for connecting the body to a doll's head, a plurality of members simulating coils of platted hair, and adhesive connecting said coils with the body.

2. A doll's wig comprising a body formed of a plurality of yarns arranged substantially parallel, a central line of knitting interlocking with said strands of yarn presenting a part effect, end sections of knitting interlocking with said strands of yarn for connecting the ends of the yarn together, and means co-acting with said end sections for holding the body in place on a head.

3. In a doll's wig a body formed of yarn simulating hair and constructed to present a rectangular member, a centrally positioned line of knitting extending transversely of the body, and end sections of knitting extending for the full width of the body.

4. A wig comprising a body, means for holding the same on a head and means co-acting with said body presenting what appears to be coils of hair, said means consisting of a coiled member formed of a pair of twisted strands, each strand being independently twisted with constricted portions and loose portions, the loose portions presenting means simulating sections of a platted strand.

5. A doll's wig comprising a body, a plurality of members simulating platted knots of hair, and adhesive covering one face of each knot connecting said knots to the body.

PERCIVAL HARRIS.

DISCLAIMER

1,628,591.—*Percival Harris, New York, N. Y. WIG FOR DOLLS.* Patent dated May 10, 1927. Disclaimer filed March 2, 1931, by the patentee and the exclusive licensee, *Mutual Hair Goods Co., Inc.*

Hereby enter this disclaimer to claim 5 of said United States Patent No. 1,628,591; that is to say, hereby disclaim the subject matter of said claim 5 as a part of the invention of the aforesaid United States Letters Patent No. 1,628,591.
